ABSTRACT

A driving method of a display panel is provided. The display panel includes first signal lines, second signal lines, pixel structures, first signal line driving circuits, and second signal line driving circuits. The first signal line driving circuits divide the first signal lines into first signal line groups and sequentially enable the first signal lines of the first signal line groups. In one of the first signal line groups, when one first signal line adjacent to another first signal line group is enabled, the second signal line driving circuits provide a first data signal to each of the second signal lines; and when the rest of the first signal lines are enabled, the second signal line driving circuits provide a second data signal to each of the second signal lines. The first data signal and the second data signal have different waveforms to display a predetermined gray scale.

DRIVING METHOD OF DISPLAY PANEL

CROSS-REFERENCE TO RELATED
APPLICATION

This application claims the priority benefit of China application serial no. 201711055567.9, filed on Nov. 1, 2017. The entirety of the above-mentioned patent application is hereby incorporated by reference herein and made a part of this specification.

BACKGROUND OF THE INVENTION

1. Field of the Invention

The invention relates to a driving method. More particularly, the invention relates to a driving method of a display panel.

2. Description of Related Art

As popularity of electronic devices grows, the display technologies continue to advance, so as to satisfy requirements from increasing types of applications. Taking electronic paper display panels for example, the electronic paper display panels are able to provide a display effect similar to that of the physical paper and feature a characteristic of power saving. The electronic paper display panels are thus introduced in more and more products. The circuit design and the driving methods of the electronic paper display panels are constantly improved for reducing border sizes so as to provide larger effective display areas. Nevertheless, regardless of the methods to be adopted, the electronic paper display panels are required to provide a uniform display effect.

SUMMARY OF THE INVENTION

The invention provides a driving method of a display panel which allows the display panel to provide a uniform display effect.

In the driving method of the display panel provided by an embodiment of the invention, the display panel includes a plurality of first signal lines, a plurality of second signal lines, a plurality of pixel structures, a plurality of first signal line driving circuits, and a plurality of second signal line driving circuits. Each of the pixel structures is driven by one of the first signal lines and one of the second signal lines to display a gray scale. The driving method provided by an embodiment of the invention includes that the first signal line driving circuits divide the first signal lines into a plurality of first signal line groups and sequentially enable the first signal lines of the first signal line groups; the second signal line driving circuits provide a first data signal to each of the second signal lines when one first signal line in one of the first signal line groups adjacent to another first signal line group is enabled, and the second signal line driving circuits provide a second data signal to each of the second signal lines when the rest of the first signal lines in the same first signal line group are enabled. The first data signal has a first waveform to display a pre-determined gray scale, the second data signal has a second waveform to display the pre-determined gray scale, and the first waveform is different from the second waveform.

In an embodiment of the invention, a cycle of the first waveform is identical to a cycle of the second waveform.

2

In an embodiment of the invention, a pulse width of the first waveform is different from a pulse width of the second waveform.

In an embodiment of the invention, a pulse height of the first waveform is different from a pulse height of the second waveform.

In an embodiment of the invention, the first data signal provided by the second signal line driving circuits has a first adjustment waveform when the first signal line adjacent to the previous first signal line group in one of the first signal line groups is enabled; the first data signal provided by the second signal line driving circuits has a second adjustment waveform when the first signal line adjacent to the following first signal line group in the same first signal line group is enabled; and the first adjustment waveform to display the pre-determined gray scale to be displayed is different from the second waveform to display the pre-determined gray scale to be displayed.

20 In an embodiment of the invention, a cycle of the first adjustment waveform is identical to a cycle of the second adjustment waveform.

In an embodiment of the invention, a pulse width of the first adjustment waveform is different from a pulse width of the second adjustment waveform.

25 In an embodiment of the invention, a pulse height of the first adjustment waveform is different from a pulse height of the second adjustment waveform.

In an embodiment of the invention, the first signal line 30 driving circuits connect an i-th one of the first signal lines of each of the first signal line groups and an i-th one of the first signal lines of the rest of the first signal line groups to a first signal source through identical transmission lines in different time sequences to enable the first signal lines, and i is a positive integer.

35 In an embodiment of the invention, a number of the transmission lines is M, i is less than or equal to M, and M is a positive integer.

In an embodiment of the invention, a number of the first 40 signal lines is N, a number of the transmission lines is M, M is less than N, and both M and N are positive integers.

To sum up, in the driving method of the display panel provided by the embodiments of the invention, the data signals can be adjusted, display inconsistency in the display panel is therefore be improved.

45 To make the aforementioned and other features and advantages of the invention more comprehensible, several embodiments accompanied with drawings are described in detail as follows.

BRIEF DESCRIPTION OF THE DRAWINGS

The accompanying drawings are included to provide a further understanding of the invention, and are incorporated in and constitute a part of this specification. The drawings illustrate embodiments of the invention and, together with the description, serve to explain the principles of the invention.

FIG. 1 is a local schematic view of a display panel 50 according to an embodiment of the invention.

FIG. 2 is a schematic diagram of signals of a first driving circuit and a transmission line according to an embodiment of the invention.

FIG. 3 are schematic diagrams of different data signals 55 displaying an identical pre-determined gray scale in a driving method of a display panel according to an embodiment of the invention.

FIG. 4 schematically illustrates signals input to second signal lines to display a pre-determined gray scale when the first signal line **110a** and the first signal line **110e** are enabled.

DESCRIPTION OF THE EMBODIMENTS

FIG. 1 is a partial schematic view of a display panel according to an embodiment of the invention. As shown in FIG. 1, a display panel **100** includes a plurality of first signal lines **110**, a plurality of second signal lines **120**, a plurality of pixel structures **130**, first signal line driving circuits **140**, and second signal line driving circuits **150**. The first signal line **110** and the second signal line **120** extend in different directions and are staggered to each other. The pixel structures **130** are disposed in an array between the first signal lines **110** and the second signal lines **120** mutually intersected, and each of the pixel structures **130** is driven by one of the first signal lines **110** and one of the second signal lines **120** for displaying an image. The first signal line driving circuits **140** and the second signal line driving circuits **150** are configured to input corresponding signals to the first signal lines **110** and the second signal lines **120**.

In this embodiment, each of the pixel structures **130** may include an active element **132** and a display unit **134** connected to the active element **132**. The display unit **134** may include a display medium (not shown) and other components configured to control a state of the display medium (e.g., a pixel electrode, a counter electrode, a storage capacitor, etc.). In this embodiment, the display medium may be an electrophoretic display medium, an electrowetting display medium, etc. and may selectively be a substance featuring a characteristic of bistability to control the displayed light. The active element **132** may be connected to one of the first signal lines **110** and one of the second signal lines **120**. The signals transmitted over the first signal lines **110** are configured to control the active elements **132** to be turned on or turned off. When the signals transmitted over the first signal lines **110** turn on the active elements **132**, the first signal lines **110** may be viewed to be enabled. When the active elements **132** are turned on, the signals transmitted over the second signal lines **120** may be input to the display units **134** through the active elements **132** being turned on. At this time, the display units **134** may present a pre-determined gray scale according to the signals received so as to provide an image displaying function. Therefore, the first signal lines **110** acting as scan lines and the second signal lines **120** acting as data lines are taken as an example for explanation in this embodiment, which should however not be construed as a limitation to the invention.

The first signal line driving circuits **140** are configured to control a signal input of the first signal lines **110**. For instance, the first signal line driving circuits **140** may divide the first signal lines **110** into a plurality of first signal line groups **G110**. The display panel **100** may further include a plurality of transmission lines **160** and a first signal source **170**. The transmission lines **160** are connected between the first signal line driving circuits **140** and the first signal source **170**. The first signal source **170** is configured to provide the signals to be input to the first signal lines **110**, and the signals from the first signal source **170** are input to the corresponding first signal lines **110** through being transmitted by the transmission lines **160** and operated by the first signal line driving circuits **140**.

In this embodiment, a number of the first signal lines **110** is **N**, and a number of the transmission lines **160** is **M**. Both

N and **M** are positive integers, and **N** is greater than **M**. In FIG. 1, **M** is illustrated as 5 as an example, but in other embodiments, **M** can be other positive integers. As shown in FIG. 1, the first signal line driving circuits **140** may group **M** first signal lines **110** into one first signal line group **G110**. The first signal lines **110** in the same first signal line group **G110** may be respectively connected to the transmission lines **160**. To be specific, an **i**-th one of the first signal lines **110** in one first signal line group **G110** may be correspondingly connected to an **i**-th one of the transmission lines **160**, wherein **i** is a positive integer and is less than or equal to **M**. For instance, a first one of the first signal lines **110a** is correspondingly connected to a first one of the transmission lines **160a**, a second one of the first signal lines **110b** is correspondingly connected to a second one of the transmission lines **160b**, a third one of the first signal lines **110c** is correspondingly connected to a third one of the transmission lines **160c**, a fourth one of the first signal lines **110d** is correspondingly connected to a fourth one of the transmission lines **160d**, and a fifth one of the first signal lines **110e** is correspondingly connected to a fifth one of the transmission lines **160e**.

In this embodiment, the first signal line driving circuits **140** may control each of the first signal line groups **G110** to be electrically connected to or not to be electrically connected to the transmission lines **160**. For instance, the first signal line driving circuits **140** may select one of the first signal line groups **G110** to be electrically connected to the transmission lines **160**, while the rest of the first signal line groups **G110** are allowed not to be electrically connected to the transmission lines **160**. At this time, the first signal source **170** may provide the signals to the first signal line **160a** to the fifth signal line **160e** in sequence. As such, in the first signal line groups **G110** electrically connected to the transmission lines **160**, the first one of the first signal lines **110a** to the fifth one of the first signal lines **110e** may be sequentially enabled after sequentially receiving the signals provided by the first signal source **170**.

FIG. 2 is a schematic diagram of signals of a first driving circuit and a transmission line according to an embodiment of the invention. With reference to FIG. 1 and FIG. 2 together, a signal **SG110a** and a signal **SG110b** are respectively configured to select signals of a first signal line group **G110a** and a first signal line group **G110b**. A signal **S160a** is a signal provided to the transmission line **160a** by the first signal source **170**, a signal **S160b** is a signal provided to the transmission line **160b** by the first signal source **170**, a signal **S160c** is a signal provided to the transmission line **160c** by the first signal source **170**, a signal **S160d** is a signal provided to the transmission line **160d** by the first signal source **170**, and a signal **S160e** is a signal provided to the transmission line **160e** by the first signal source **170**.

The first signal line driving circuits **140** select the first signal line group **G110a** to be connected to the transmission lines **160** according to the signal **SG110a**. At this time, the first signal line **110a** of the first signal line group **G110a** may receive a signal transmitted by the transmission line **160a**, the first signal line **110b** of the first signal line group **G110a** may receive a signal transmitted by the transmission line **160b**, the first signal line **110c** of the first signal line group **G110a** may receive a signal transmitted by the transmission line **160c**, the first signal line **110d** of the first signal line group **G110a** may receive a signal transmitted by the transmission line **160d**, and the first signal line **110e** of the first signal line group **G110a** may receive a signal transmitted by the transmission line **160e**. Meanwhile, since the first signal line group **G110b** is not electrically connected to the trans-

mission lines 160, the first signal line 110a to the first signal line 110e in the first signal line group G110b do not receive signals.

Next, the first signal line driving circuits 140 select the first signal line group G110b to be connected to the transmission lines 160 according to the signal SG110b. At this time, the first signal line 110a to the first signal line 110e of the first signal line group G110b may sequentially receive the signals transmitted by the transmission line 160a to the transmission line 160e. Meanwhile, since the first signal line group G110a is not electrically connected to the transmission lines 160, the first signal line 110a to the first signal line 110e in the first signal line group G110a do not receive signals. In this way, in the display panel 100 of this embodiment, as the number of the transmission lines 160 is less than the number of the first signal lines 110, signal transmission of the first signal lines 110 are thereby achieved. Since the number of the transmission lines 160 is lowered, the display panel 110 may have a relatively narrow border width and thus can provide a relatively large display area as required.

The second signal line driving circuits 150 provide data signals to the second signal lines 120, such that, the corresponding pixel structures 130 are input by the corresponding data signals for presenting the corresponding gray scale so as to display an image. Generally, the data signals provided by the second signal line driving circuits 150 may determine the gray scale to be displayed by the pixel structures 130. Nevertheless, when all of the pixel structures 130 of the display panel 100 are written by the same data signals, in certain circumstances, it can be seen that the gray scale presented by the pixel structures 130 in a vicinity of boundaries of different first signal line groups G110 are different from that presented by the rest of the areas. Such inconsistency brings an evident display fault and leads to poor display quality of the display panel 100. The fault is even more apparent when all of the pixel structures 130 are enabled to present the same gray scale by the display panel 100. For instance, when a white image or a black image is displayed on the entire display panel 100, periodic gray lines may be presented in the image. Therefore, in the driving method of the display panel 100 provided by this embodiment, the data signals with different waveforms are adopted and are transmitted to the pixel structures 130 located in different areas for presenting the same pre-determined gray scale, so as to resolve the foregoing problem.

FIG. 3 are schematic diagrams of different data signals displaying an identical pre-determined gray scale in a driving method of a display panel according to an embodiment of the invention. With reference to FIG. 1 and FIG. 3 together, in this embodiment, the first signal line driving circuits 140 may be driven by adopting the signals of FIG. 2, such that the first signal lines 110 of the first signal line groups G110 are sequentially enabled. When one first signal line 110 (e.g., 110a or 110e) in one of the first signal line groups G110 adjacent to another first signal line group G110 is enabled, a first data signal S120a is provided to each of the second signal lines 120 by the second signal line driving circuits 150. When the rest of the first signal lines 110 (e.g., 110b to 110d) in the same one of the first signal line groups G110 are enabled, a second data signal S120b is provided to each of the second signal lines 120 by the second signal line driving circuits 150. As shown in FIG. 3, the first data signal S120a to display the pre-determined gray scale and the second data signal S120b to display the same pre-determined gray scale respectively have a first waveform WFa and a second waveform WFb. The first waveform WFa is different from the second waveform WFb.

In this embodiment, the first data signal S120a having the first waveform WFa is input to the respective second signal lines 120 in a time period during which the signal of the transmission line 160a or the transmission line 160e is at a high level. The second data signal S120b having the second waveform WFb is input to the respective second signal lines 120 in a time period during which the signals of the transmission line 160b to the transmission line 160d are at a high level. As such, the pixel structures 130 connected to the first signal line 110a and the first signal line 110e may receive the first data signal S120a, and the pixel structures 130 connected to the first signal line 110b to the first signal line 110d may receive the second data signal S120b.

As shown in FIG. 3, the first waveform WFa has a first period Ta, the second waveform WFb has a second period Tb, and the first period Ta and the second period Tb are the same. As such, although the first data signal S120a and the second data signal S120b have different waveforms, the driving method of this embodiment may be performed at a fixed image updating rate. In addition, a pulse width WPa of the first waveform WFa is different from a pulse width WPb of the second waveform WFb, wherein the pulse width WPa of the first waveform WFa is illustrated to be less than the pulse width WPb of the second waveform WFb, which should however not be construed as a limitation to the invention. The first data signal S120a and the second data signal S120b are configured to display the same pre-determined gray scale; hence, a pulse height WHa of the first waveform WFa and a pulse height WHb of the second waveform WFb may be identical to each other in this embodiment. Therefore, after being input to the corresponding pixel structures 130, even though the first waveform WFa and the second waveform WFb are different, the identical gray scale may be presented by the pixel structures 130 in a vicinity of boundaries of different first signal line groups G110 and the rest pixel structures 130. Through such a driving method, the display panel 100 is able to provide favorable displaying uniformity.

In addition, in some embodiments, the data signals with different waveforms may also be adopted by the pixel structures 130 on the first signal line 110a and the pixel structures 130 on the first signal line 110e, so as to display the identical pre-determined gray scale. For instance, FIG. 4 schematically illustrates the signals input to the second signal lines to display the pre-determined gray scale when the first signal line 110a and the first signal line 110e are enabled. With reference to FIG. 4, when the first signal line 110a is enabled, a signal input to the second signal lines 120 to display the pre-determined gray scale may be one of a first data signal S120a1 and a first data signal S120a2. When the first signal line 110e is enabled, a signal input to the second signal lines 120 to display the pre-determined gray scale may be the other one of the first data signal S120a1 and the first data signal S120a2. The first data signal S120a1 has a first adjustment waveform WFa1, and the first data signal S120a2 has a second adjustment waveform WFa2. Here, both the first adjustment waveform WFa1 and the second adjustment waveform WFa2 are both different from the waveform WFb in FIG. 3. Besides, although both the first adjustment waveform WFa1 and the second adjustment waveform WFa2 are configured to allow the corresponding pixel structures 130 to display the same gray scale, the first adjustment waveform WFa1 and the second adjustment waveform WFa2 are different from each other. For instance, a pulse width WPa1 in the first adjustment waveform WFa1 is different from a pulse width WPa2 in the second adjustment waveform WFa2. Nevertheless, a period Ta1 of the

first adjustment waveform WFa1 is identical to a period Ta2 of the second adjustment waveform WFa2, and a pulse height WHa1 of the first adjustment waveform WFa1 is identical to a pulse height WHa2 of the second adjustment waveform WFa2. FIG. 4 illustrates that the pulse width WPa1 is less than the pulse width WPa2 for description, but in other embodiments, the two pulse widths can be adjusted according to different requirements.

In the foregoing embodiments, differences among different waveforms may be adjusted according to the inspection and test of the display panel 100. For instance, when a full-screen of white image is displayed by one manufactured display panel 100 and a defect of gray lines appears on the white image. The waveforms of the data signals of the pixel structures located in the vicinity of the boundaries of different first signal line groups may be adjusted, so as to allow the gray scale presented to be biased towards white. When a full-screen of black image is displayed by one manufactured display panel 100 and a defect of gray lines appears on the black image. The waveforms of the data signals of the pixel structures located in the vicinity of the boundaries of different first signal line groups can be adjusted, so as to allow the gray scale presented to be biased towards black. Such signal adjustment may be repeatedly performed until the display uniformity of the display panel 100 is achieved as required. The driving method of the display panel 100 is to drive each of the pixel structures 130 by the signals adjusted through the foregoing methods. In the manufacturing process, such signals being adjusted may be directly applied to the display panel 100 manufactured in batches, and said inspection and test are thereby not required to be performed on every display panel.

In view of the foregoing, in the display panel provided by the embodiments of the invention, the waveforms of the signals input to some of the pixel structures to display the pre-determined gray scale are adjusted, such that the waveforms are different from that of the signals input to the rest of the pixel structures displaying the same gray scale. The first signal lines are enabled through being selected and divided into groups and being driven by the display panel; nevertheless, the pixel structures located in the vicinity of the boundaries of different groups may present the gray scale identical to that presented by the rest of the areas, and the uniform display effect is thereby achieved.

It will be apparent to those skilled in the art that various modifications and variations can be made to the structure of the present invention without departing from the scope or spirit of the invention. In view of the foregoing, it is intended that the present invention cover modifications and variations of this invention provided they fall within the scope of the following claims and their equivalents.

What is claimed is:

1. A driving method of a display panel, the display panel comprising a plurality of first signal lines, a plurality of second signal lines, a plurality of pixel structures, a plurality of first signal line driving circuits, and a plurality of second signal line driving circuits, each of the pixel structures being driven by one of the first signal lines and one of the second signal lines to display a gray scale, the driving method comprising:

dividing the first signal lines into a plurality of first signal line groups by the first signal line driving circuits and sequentially enabling the first signal lines of the first signal line groups; and

providing a first data signal to one of the second signal lines by the second signal line driving circuits when

one first signal line in one of the first signal line groups adjacent to another of the first signal line groups is enabled, and providing a second data signal to the one of the second signal lines by the second signal line driving circuits when the rest of the first signal lines in the one of the first signal line groups are enabled, wherein the first data signal and the second data signal inputted to the one of the second signal lines respectively have a first waveform and a second waveform to display a same pre-determined gray scale, and the first waveform is different from the second waveform.

2. The driving method of the display panel as claimed in claim 1, wherein a cycle of the first waveform is identical to a cycle of the second waveform.

3. The driving method of the display panel as claimed in claim 1, wherein a pulse width of the first waveform is different from a pulse width of the second waveform.

4. The driving method of the display panel as claimed in claim 1, wherein a pulse height of the first waveform is identical to a pulse height of the second waveform.

5. The driving method of the display panel as claimed in claim 1, wherein

the first data signal provided by the second signal line driving circuits has a first adjustment waveform when the first signal line in the one of the first signal line groups adjacent to a previous first signal line group is enabled,

the first data signal provided by the second signal line driving circuits has a second adjustment waveform when the first signal line in the one of the first signal line groups adjacent to a next first signal line group is enabled, and

the first adjustment waveform to display the pre-determined gray scale is different from the second waveform to display the pre-determined gray scale.

6. The driving method of the display panel as claimed in claim 5, wherein a cycle of the first adjustment waveform is identical to a cycle of the second adjustment waveform.

7. The driving method of the display panel as claimed in claim 5, wherein a pulse width of the first adjustment waveform is different from a pulse width of the second adjustment waveform.

8. The driving method of the display panel as claimed in claim 5, wherein a pulse height of the first adjustment waveform is identical to a pulse height of the second adjustment waveform.

9. The driving method of the display panel as claimed in claim 1, wherein the first signal line driving circuits connect an i-th first signal line of the first signal lines of each of the first signal line groups and an i-th first signal line of the first signal lines of another of the first signal line groups to a first signal source through identical transmission lines in different time sequences to enable the first signal lines, and i is a positive integer.

10. The driving method of the display panel as claimed in claim 9, wherein a number of the transmission lines is M, a number of the first signal lines is N, i is less than or equal to M, M is less than N, and both M and N are positive integers.
